UNITED STATES PATENT OFFICE

161,983

BICYCLE OR SIMILAR ARTICLE

Samuel Wilkens, East Rockaway, N. Y.

Application June 19, 1950, Serial No. 10,625

Term of patent 14 years

(Cl. D90—8)

To all whom it may concern:

Be it known that I, Samuel Wilkens, a citizen of the United States, residing at East Rockaway, in the county of Nassau and State of New York, have invented a new, original, and ornamental Design for a Bicycle or Similar Article, of which the following is a specification, reference being had to the accompanying drawing, forming a part thereof.

Fig. 1 is a perspective view of a bicycle or similar article, showing my new design.

Fig. 2 is a section taken on line 2—2 of Fig. 1.

The dominant features of the design reside in the portions shown in full lines.

I claim:

The ornamental design for a bicycle or similar article, substantially as shown and described.

SAMUEL WILKENS.
